UNITED STATES PATENT OFFICE.

CORNELIS KLOOS, OF BUSSUM, NETHERLANDS.

DEVICE FOR SUPPLYING A COOLING LIQUID TO PISTONS OF INTERNAL-COMBUSTION ENGINES.

1,334,866.

Specification of Letters Patent. Patented Mar. 23, 1920.

Application filed January 29, 1919. Serial No. 273,857.

To all whom it may concern:

Be it known that I, CORNELIS KLOOS, engineer, subject of the Queen of the Netherlands, residing at Bussum, Netherlands, have 5 invented certain new and useful Improvements in Devices for Supplying a Cooling Liquid to Pistons of Internal-Combustion Engines, of which the following is a specification.

10 The present invention relates to a device for supplying a cooling liquid to the piston of an internal combustion engine.

It has been proposed to realize such supply, respectively the removal of the liquid 15 from the piston, by means of a pair of telescopic tubes one of which is affixed to the piston and executes a reciprocating motion within the second tube. With some of these known devices the supply of the liquid is 20 realized under a certain pressure in which case a stuffing-box must be provided between both tubes, in other devices the liquid is introduced in form of a jet into the piston and leaves the latter by the telescopic tubes.

25 According to the present invention the cooling liquid is supplied to the piston exclusively by the dynamic energy of the latter and by means of a pair of telescopic tubes of special construction. In the stationary 30 tube which has the largest diameter the liquid is kept at a constant level of such height that the second tube which is affixed to the piston dips into the liquid at each downward stroke. The characteristic feature of 35 the device according to the invention is that the second tube has such a shape, respectively is provided with such means that the liquid when penetrating into it is subject to a smaller resistance than at leaving the tube.

40 In consequence the reciprocating tube receives more liquid during its downward motion than it renders during its upward motion, the differential quantity being transmitted at each stroke to the piston.

45 Three tubes having the above mentioned effect are shown by the accompanying drawing. In all of the figures 1 is the hollow piston, 2 the dipping tube, 3 the stationary tube of larger diameter, into which the liquid is supplied by the tube 4, the level being kept constant by means of an overflow tube 5.

With the dipping tube 2 according to Figure 1 the different resistance in both senses is obtained by means of a mouth piece in the 55 shape of a nozzle arranged at the lower end

of the dipping tube and provided at its inner end with a sharp edge. When liquid is flowing downward through the tube said edge causes a contraction of the jet the quantity of liquid issuing per time unit being consequently smaller than the quantity of liquid flowing per time unit through the mouth piece into the tube under equal circumstances.

According to Fig. 2 the dipping tube is 60 provided at its inner surface with a number of oblique baffle plates affixed with one end to the tube and extending approximately to the axis of the latter.

Fig. 3 represents a dipping tube with a 65 closed lower end above which a series of openings are provided. At the downward stroke of the piston the liquid penetrates into the tube through the openings at its lower end; at the upward stroke the greater part 70 of this quantity of liquid is transmitted to the piston by inertia.

Having now described my invention I declare that what I claim is:

1. In a device for supplying a cooling liquid to a hollow piston of an internal combustion engine, the combination with a stationary tube having a water inlet at its lower end and an outlet at a determined point to maintain a water level in said tube, of a hollow reciprocating piston, a tube mounted to reciprocate with said piston in the stationary tube, the reciprocating tube having an open end discharging into said piston and the bottom of said tube being closed, and provided 80 at a determined distance above the closed bottom with a series of openings, the space in the tube below the openings forming a pocket to receive water, whereby, when the tube is reciprocated, the water in the stationary tube will be caused to flow through the openings and accumulate in the pocket, and the water in the pocket will, by momentum 85 in the reciprocation of the tube, be forced 90 upwardly and into the hollow piston. 95

2. In a device for supplying a cooling liquid to a hollow piston of an internal combustion engine, the combination with a stationary tube having a water inlet at its lower end and an outlet at a determined point to 100 maintain a water level in said tube, of a hollow reciprocating piston, a tube mounted to reciprocate with said piston in the stationary tube, the reciprocating tube having an open end discharging into said pis- 105

ton and the bottom of said tube being closed and pointed, and provided at a determined distance above the pointed end with openings, the space in the pointed closed end of the tube below the openings forming a pocket to receive water, whereby, when the tube is reciprocated, the water in the stationary tube will be caused to flow through the openings and accumulate in the pocket, and the

water in the pocket will, by momentum in 10 the reciprocation of the tube, be forced upwardly and into the hollow piston.

In testimony whereof I affix my signature.

CORNELIS KLOOS.
